UNITED STATES PATENT OFFICE

XAVER DAMBACHER, OF LENGERICH/WESTPHALIA, GERMANY, ASSIGNOR TO THE FIRM WINDMÖLLER & HÖLSCHER, G. M. B. H., OF LENGERICH/WESTPHALIA, GERMANY

METHOD OF AND APPARATUS FOR DETACHING SHEETS OF PAPER OF UNIFORM LENGTH

Application filed December 28, 1928, Serial No. 328,917 and in Germany February 6, 1928.

The invention relates to the detaching of sheets of paper of uniform length from a plurality of paper webs in such manner that the edges of the separate sheets, situated transversely in relation to the direction of the webs, are relatively offset stepwise.

According to the invention, the paper webs are divided up into the desired lengths by means of rows of perforations or equivalent (hereinafter termed "weakening lines") running crosswise of the direction of the webs, and the webs thus prepared are fed conjointly through a pair of draft rollers in such manner that the weakening lines are superimposed stepwise after which the webs are torn-off or separated along the weakening lines.

The usual cutting and detaching mechanism is replaced by a pair of tearing rollers running at a higher speed than the aforesaid draft rollers. By this means, the coming into action of the tearing rollers exerts a pull or jerk on the paper webs in the longitudinal direction of same, so as to tear off the lengths or sheets from the paper webs along the staggered weakening lines.

A typical embodiment of the invention is illustrated diagrammatically on the accompanying drawing, on which Fig. 1 is a side elevation; and Fig. 2 is a plan of the perforated paper web and of the position of the paper detached in accordance with the new method.

The paper webs 1':2':3' coming from the reels 1:2:3, are passed through pairs of perforating cylinders 4 and 5:6 and 7:8 and 9, being thus provided with lines of perforations 1":2":3". The webs are then led over guide rollers 10 and 11 and passed conjointly between draft rollers 12 and 13, the feed being arranged so that the weakening lines 40 1":2":3" produced by the rollers 4 and 5 etc., assume the relatively stack-shaped or stepwise positions shown in Fig. 2. From the draft rollers, the paper webs are fed to tearing rollers 17 and 18, the upper roller 18 of 45 which is mounted in a pair of levers 14 and 15 and is moved up and down by an eccentric 16. These tearing rollers 17 and 18 have a higher peripheral velocity than the draft rollers 12 and 13 so that, when the upper roller 18 comes into touch with the lower roller

17, the difference in the peripheral velocity of the two pairs of rollers 12:13 and 17:18 acts on the multiple paper web, and tears the same apart at the perforations or weakening lines 1":2":3".

I claim:

1. A method of mechanically producing sheets of paper, disposed in stepwise manner, from a plurality of webs, consisting in marking off the webs into the desired lengths 60 of sheet by transverse weakening lines, then feeding the webs conjointly so that the weakening lines of the different webs are relatively offset stepwise, and thereafter subjecting the webs to a tensioning action to separate the 65 sheets along said weakening lines.

2. A machine for producing sheets of paper, disposed in stepwise manner, from a plurality of paper webs, comprising a plurality of reel supports; means for marking 70 off the webs into the desired lengths of sheet while being fed from the reels; guide rollers arranged to bring the webs into superimposition with the weakening lines offset stepwise; means for feeding the webs, and tensioning means acting in conjunction with the last recited means to separate the sheets along 75 said weakening lines.

3. A machine for producing sheets of paper, disposed in stepwise manner, from a 80 plurality of paper webs, comprising a plurality of reel supports, means for marking off the webs into the desired lengths of sheet while being fed from the reels, guide rollers and draft rollers arranged to bring the webs 85 into superimposition with the weakening lines offset, tensioning means for separating the sheets along the weakening lines, and means for operating the aforesaid means and draft rollers.

4. A machine for producing sheets of paper, disposed in stepwise manner, from a plurality of paper webs, comprising a plurality of reel supports, perforating rollers for marking off the webs into the desired lengths 85 of sheet by rows of transverse perforations while being fed from the reels, guide rollers arranged to bring the webs into superimposition with their perforations relatively offset stepwise, means for feeding the webs, and 130

tensioning means acting in conjunction with the last recited means to separate the sheets along said perforations.

5. A machine for producing sheets of paper, disposed in stepwise manner, from a plurality of paper webs, comprising a plurality of reel supports, perforating rollers for marking off the webs into the desired lengths of sheet by rows of transverse perforations while being fed from the reels, guide rollers and draft rollers arranged to bring the webs into superimposition with their perforations relatively offset stepwise, tensioning means for separating the sheets along the perforations, and means for operating the aforesaid perforating rollers, draft rollers and tensioning means.

6. In the method of mechanically producing sheets of paper, disposed in stepwise relation, from a plurality of webs having transverse weakening lines defining the several sheets, the step which consists in conjointly feeding the webs with the weakening lines of the several webs in relatively offset relation before detaching the sheets.

7. In the method of mechanically producing sheets of paper, disposed in stepwise relation, from a plurality of webs having transverse weakening lines defining the several sheets, the steps which consist in conjointly feeding the webs with the weakening lines of the several webs in relatively offset relation, and simultaneously detaching corresponding sheets of the several webs by tension.

35 In testimony whereof I have affixed my signature.

XAVER DAMBACHER.
